(57) **CLAIM**

The ornamental design for a digital camera, as shown and described.

DESCRIPTION

FIG. 1 is a top, front and right-side perspective view of a digital camera showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is top plan view thereof;
FIG. 7 is bottom plan view thereof; and,
FIG. 8 is an enlarged view of a lens member, the rest of the camera is omitted for ease of illustration.
The portions of the digital camera in broken lines in FIGS. 1, 2, 3, 4, 5, 6 and 7 are shown to illustrate environment only and form no part of the claimed design.
